WANDERER-WERKE, VORM. WINKLHOFER & JAENICKE, A. G., OF CHEMNITZ, GER-
MANY.

ACCENT MECHANISM FOR TYPE-WRITERS.

1,154,286.

Specification of Letters Patent. Patented Sept. 21, 1915.

Application filed March 27, 1913. Serial No. 757,244.

To all whom it may concern:

Be it known that I, THEODOR EUGEN BUSCHMANN, a subject of the King of Saxony, and resident of Haydnstrasse 9, 5 Chemnitz, Saxony, Germany, have invented new and useful Improvements in Accent Mechanism for Type-Writers, of which the following is a specification.

This invention relates to an improved 10 device for typing accents and similar signs for use in typewriting machines.

It is a well known fact that in devices of 15 this type provisions must be made which, when an accent key is struck, prevent the carriage feed mechanism from coming into operation, as otherwise the accent in question would not be typed above the letter to which it belongs.

In existing devices serving a similar purpose 20 the feed of the paper carriage is prevented by providing the accent key with notches or recesses located above the so-called universal bar, so that, on depressing the accent key, no movement is imparted to this universal bar. In these existing devices, however, it is one of the conditions 25 that accents or similar signs are always allotted to the same keys, so that they cannot be grouped with other characters, for instance, with numerals or letters. This restriction is particularly inconvenient in 30 cases where the key board must comprise an uneven number of accent signs, since in such cases it will be necessary to provide 35 a separate key for the sake of a single sign.

The object of this invention is to provide 40 means to obviate this drawback. On shifting the platen by means of the shift key a system of levers is thrown into action which in its turn throws into operation an adjustment piece which, so to speak, fills out or supplements the notches or recesses in the accent keys so that these keys may act either as "dead" keys, (i. e. keys which do 45 not influence the paper carriage feed mechanism) or as normal keys. By adopting this arrangement it is possible to group together accents or similar signs with numerals, ordinary letters and the like on the 50 same carriers, so that during the writing of numerals and the like, the corresponding key may act as a normal key, while when typing accents the recess or notch in the accent key is uncovered by the movement 55 of the carriage-shifting or case changing

frame and the key in question may be converted into a "dead" key.

One method of carrying the invention into effect is shown by way of example in the accompanying drawings in which:—

Figure 1 is a side elevation of the key and type lever system together with their appertaining rods of a typewriting machine. Fig. 2 is a view of a detail in a different position and Fig. 3 shows views of some keys, each of which is provided with an accent or the like sign as well as with an ordinary character or symbol. Fig. 4 shows the mechanism applied to a normally dead key.

In the example of the invention illustrated the platen S is mounted in the ordinary manner on the carriage-shifting frame by means of guide rollers, so that it may be moved to and fro.

2 denotes a type lever segment in which the type levers 3 are preferably mounted on balls. The type levers 3 receive their movement from the key levers in the usual way through the medium of intermediate levers 4. Of the aforesaid key levers one accent key lever 5 is shown in Fig. 1. The free end of the shift key lever 6, which is adapted to rock about the pivot 7 is jointed by means of a rod system 8 to the carriage-shifting frame 1, to which latter, for the purpose of insuring a parallel motion, there is further hinged an arm 9 secured to the rocking shaft 10. To said rocking shaft 10 there is further fixed an arm 11 which is jointed to a connecting rod 12, the other end of which is pivoted to an adjustment piece, 14 which is suspended from an extension 5^a of the accent key lever 5 in such a manner that it may rock. Further there is provided a spring 13 which connects the arm 11 to the connecting rod 12 and which spring tends to pull the connecting rod always toward the left (Fig. 1). At the connecting point between the arm 11 and the connecting rod 12 provision is made for some lost motion, for which purpose a longitudinal slot 12^a is provided in the connecting rod 12. Beneath the key levers there is arranged in the usual manner, a universal bar 15 which is mounted on a shaft 17 by means of a member 16. The said shaft 17, through the medium of the rods 18 and 19 transmits the motion to the carriage feed mechanism. The remainder of the lever mechanism, which is not further de-

scribed herein, serves for transmitting the necessary motion for driving the ribbon fork also during the typing of accents.

The keys illustrated in Fig. 3 show one example of how ordinary characters or numerals may be grouped together with accents and similar signs according to this invention.

The mode of operation of the improved device for typing accents and similar signs is as follows:—Assuming that in the illustrated example the ordinary characters are arranged in the bottom row, it will be necessary to depress the shift key for typing accents. On depressing the shift key the case shifting frame 1, is raised by means of the rod system 8 and transmits the motion to the rocking shaft 10 through the medium of the arms 9, which shaft at the same time causes the shorter arm 11 to be turned to the right. In this case the rod 12 and with it the adjustment piece 14, are moved from the position shown in Fig. 2 into the position shown in Fig. 1. If now the accent key lever 5 is depressed, it does not cause the carriage to travel, as said lever cannot influence the universal bar 15, owing to the notch or recess above said bar being now uncovered. The case, however, is different when the parts are in their normal position shown in Fig. 2, in which the carriage is not shifted by the shift key. In this position, the adjustment piece 14 presses on the universal bar 15 and thus causes the carriage feed mechanism to operate. Should the platen or the carriage-shifting frame move downward, without the universal bar also moving downward to a sufficient extent, the spring 13 arranged between the rocking lever 11 and the rod 12 is tensioned (Fig. 1), said spring causing the adjustment piece 14, after the complete descent of the universal bar, to return into its normal position.

It is evident from the above that this invention renders it possible to group together accents or similar signs with any desired character on a particular carrier, so as to meet the requirements arising in each particular case out of the arrangement of the key board, it being immaterial, whether the accent sign is moved into the operative position by manipulating the shift key, or whether it assumes the said position when the platen is in its normal position. If the accent signs are to be in their operative position during normal typing, (*i. e.* without using the shift key), all that is necessary is to so modify the arrangement that normally the accent key acts as "dead" key, while when it is desired to type ordinary characters, the aforesaid key, when the carriage is shifted by means of the shift key, is converted into a normal key. This is done without essentially changing the mechanism as illustrated in Fig. 4 when lever 14 that

controls the notch is inclined to normally expose the notch. This is done by simply shortening lever 12 so that the notch in the key lever 5 is exposed for lower case writing and acts as a dead key without stepping the platen, while when the shift key 6 is actuated, the lever 14 is swung over the notch and causes the type lever 5 to act as an ordinary key and operate the universal bar 15.

I claim:

1. In a typewriting machine having a universal bar and platen shifting mechanism, a key lever having a notch over said universal bar and normally acting as a dead key lever in one position of the platen, and notch closing means actuated from the platen shifting means when the platen is in another position and causing said key lever to act as a live key lever.

2. In a typewriting machine having a universal bar and platen shifting mechanism, a key lever and means on said lever moved into and out of operative relation to said universal bar by the shifting mechanism.

3. In a type writing machine having a universal bar and platen shifting mechanism, a key lever having a notch located opposite the universal bar, a lever pivoted to the key lever and operating as a notch filler and means to connect said lever to the shifting mechanism, whereby said pivoted lever is moved into and out of operative position over the universal bar.

4. In a typewriting machine having a carriage shifting mechanism, and a universal bar, a special type lever with a recess adapted to permit the depression of the said lever without depressing the universal bar, an adjustment piece on the type lever adapted to fill out the recess and to cause the said type lever to act as a normal type-lever, and a shift key adapted to put the adjustment piece into or out of normal operating position.

5. In a typewriting machine having a carriage shifting mechanism and a universal bar, a special type lever having a recess therein adapted to permit the depression of the said lever without depressing the universal bar, an adjustment piece to cause said lever to act as a normal type-lever, a shift key, and a system of levers attached thereto and to the adjustment piece adapted to put the adjustment piece out of operation on depressing the shift key.

6. In a typewriting machine having a carriage shifting mechanism and a universal bar, a special type lever having a recess therein to permit its depression without depressing the universal bar, an adjustment piece on said lever pivotally connected thereto, and adapted to fill out the depression and to cause the lever to act as a normal type lever, a shift key, a link thereon, a bell

crank lever connected to the link by one of its arms, and a link on the other arm pivotally connected to the adjustment piece to operate the said adjustment piece so as to fill out the depression in the type lever on depressing the above mentioned shift key.

7. In a typewriting machine having a carriage traversing mechanism and a universal bar, a special type lever having a recess 10 therein, to permit its depression without depressing the universal bar, an adjustment piece on said lever pivotally connected thereto, and adapted to fill out the recess and to cause the lever to act as a normal type-lever,

a shift key, a link thereon, a bell crank lever connected to the link by one of its arms, a link pivotally connected to the adjustment piece at one end, a slot in the other end, a pin on the second arm of the bell crank lever engaging within the slot, 20 and a spring under tension connected to the link and to the said second arm.

In testimony whereof I have affixed my signature in presence of two witnesses.

THEODOR EUGEN BUSCHMANN.
